IGNITION APPARATUS

Edward B. Nowosielski, Bloomfield, N. J., assignor to Eclipse Aviation Corporation, East Orange, N. J., a corporation of New Jersey

Original application April 17, 1935, Serial No. 16,882. Divided and this application July 21, 1937, Serial No. 154,845

12 Claims. (Cl. 123—169)

This invention relates to spark plugs, and more especially to spark plugs for aviation engines. This application is a division of my application No. 16,882, filed April 17, 1935.

5 The object of this invention is to provide a spark plug, and more especially a shielded spark plug, the construction of which is such as to prolong its life and to insure its effectiveness in such service, and to afford convenience, and which is 10 economical to manufacture.

The invention comprises novel features of great utility in spark plugs, and novel combinations of elements making an improved spark plug and an improved assemblage of the spark plug and its 15 high-tension conductor.

One phase of the invention involves a novel method of insuring against development of "pipes" along the edges of the rolled mica sheets employed as part of the insulating means.

20 In the accompanying drawing forming part hereof:

Fig. 1 is a view in elevation of one embodiment of the invention;

Fig. 2 is a longitudinal sectional view of the 25 plug shown in Fig. 1 but on an enlarged scale;

Fig. 3 is a bottom plan view of certain of the inner elements of the plug as viewed along the plane indicated at 3—3 in Fig. 2;

Figs. 4 to 8 inclusive, indicate the appearance 30 of the element 86 of Figs. 1 and 2 as it passes through the successive stages in the process of forming it into its final condition.

For the purpose of a shielded aviation spark plug the metal body 10 of the plug is provided 35 with a shield extension 11 which extends upward considerably above the upper end of the spindle 12 to enclose the spindle and the electrical connection between the same and the conductor which leads the high-tension current to the spindle. This shield extension is preferably in one 40 piece with the attaching nut 5, though such unity is not necessary.

Instead of completely closing the space between the shield extension 11 and spindle 12, I 45 provide a cooling and ventilating chamber 13 in the form of an annular space between the shield extension 11 and a long thin cylindrical metallic sleeve 14 having low thermal conductivity, and lined with a tube 15 formed of rolled mica constituting the wall of a second chamber 16 bounded 50 at its lower end by the upper surface of the compressible metal gland 17, and at its upper end by a novel heat deflecting and sealing assembly to be further described. The gland 17, instead of resting directly upon the lower mica stack 18, as

is the usual practice, is in contact with the upper end 21 of a sleeve 22 provided for the purpose of absorbing the heat which finds its way into the mica stack 18 and deflecting said heat to the gland 17 and outer wall of the plug. Two other 5 heat deflecting sleeves are shown at 23, and 24, the former resting on the upper surface of the electrode cup 25 secured in position on the base of the spindle 12 by a pressure sufficient to change the cross-section of the upper end of the cup 10 (initially of uniform bore) and cause its contour to conform to that of the spindle base. The part 24 is in the nature of a continuous jacket enclosing the spindle 12 and its insert 27 of some metal (such as copper or silver) having higher 15 heat conductivity than the material—steel, preferably—used in the spindle proper. This sleeve or jacket 24 is shown as closed at its lower end but this closure occurs only after the jacket has been positioned upon the spindle, the jacket being 20 initially, merely a thin tube open at either end. After being placed around the spindle the extending portion of the lower end is bent inwardly to lie flat against the bottom surface of the spindle 12 and its insert 27—in other words, 25 to occupy the position indicated in Fig. 2. It will be noticed further that the jacket 24 extends upwardly to a point just above the end of the gland 17 and the point where the centrally bored portion of the spindle begins. Due to the reduction 30 in cross-sectional area at this point, and also by reason of the termination of the jacket 24 at this point, there is a tendency to cut off much of the upward flow of heat through the spindle 12 and 35 to deflect the heat flow outwardly and radially into the copper gland 17 from which much of the heat is directly dissipated by the cooling blast circulating adjacent the central flange or shoulder 31 of the gland 17, such circulation being produced 40 by reason of the radial openings 32 and the annular chamber 33 communicating therewith. The sleeves 23 and 22 coact with the jacket 24 in diverting heat from the spindle 12 and the electrode 25 to the annular chamber 34 and the copper gland 17, and from said chamber and gland to the atmosphere by way of shell 36 and radial openings 32. In or adjacent the plane of these 45 radial openings 32 there is provided a thrust washer 38 through which pressure is applied to 50 the gland 17, and a compressible hoop or washer 39 is provided to insure a firm bond or seal preventing the escape of the confined cylinder gases, the pressure being applied as a result of threading 55 the shield extension 11 into the shell 10, the

two elements just mentioned being correspondingly threaded as indicated at 41.

As shown clearly in Fig. 2, the spindle 12 is of reduced diameter at two or more points as indicated at 43 and 44; and the jacket 24, the rolled mica tube 46, and the soft metal gland 17 are pressed snugly into these peripheral depressions in the spindle as one of the plug assembling operations. This operation of applying pressure laterally results not only in a firm seal around the spindle 12 but also eliminates any longitudinally extending crevices or "pipes" which have heretofore been a source of leakage characteristic of rolled mica insulating tubes. The 10 wrapping of the mica sheets one around the other tends to leave such crevices running longitudinally of the wrapping, but by producing kinks at several points along the length of the wrapping, as indicated, I have found it possible to eliminate 15 this source of trouble.

As a means of maintaining the mica stack 48 in the compressed condition and at the same time applying radial pressure to hold the mica lining 15 of the inner metallic sleeve 14 in position, and 20 at the same time effecting an additional path for the transfer of heat directly to the said sleeve 14 from which it may be radiated to the atmosphere by the cooling current of air flowing along the chamber 13 and the radial apertures 25 20 and 26, I propose to thread the upper end 51 of the spindle 12 and apply to said threaded portion 51 a pair of threaded collars or nuts 52 and 53, the latter having an external taper to receive 30 a correspondingly internally tapered collar 54 of softer material such as copper so that it may, when subjected to the pressure applied by the tightening of nut 52, form a firm bond with the washer 55 and also with the expansion ring 58 which grips the mica lining 15 at a point approximately midway between its ends, this lining 58 being inserted and expanded in the tube 14 prior to the assembly of said tube within the shield extension 11. The associated elements 52, 53, 54 and 55, on the other hand, are first assembled 40 45 separately in position upon the inner plug assembly, and the latter is then dropped in place within the shell 36 prior to bringing the shield extension assembly into position. Also prior to attaching the upper assembly there is inserted 50 within the hollowed portion of the spindle, a coil spring 61 and a contact pin 62 having a circumferential shoulder 63 against which the upper end of the spring 61 abuts to urge said pin upwardly into position to contact the radially 55 spread strands of the current conducting wire 66 when the latter is installed in place. Associated with the wire 66 is its covering 67 of insulating material, its outer metallic sheath 68, the flanged connection 69 soldered or otherwise 60 secured thereto, and the attached coupling nut 71, all of which are brought into assembled relationship with the parts previously described.

As noted above the inner end of the conductor 66 extends below the insulating material 67 for 65 a certain distance so that the strands may be spread apart to provide better contact with the end of the pin 62. The method of fastening the spread apart ends of the conductor is indicated best in Fig. 3 and includes the provision of a flat 70 metallic plate 73 having a pair of notches 74 and 75 cut therein on opposite sides of the central aperture 76 through which the conductor 66 passes. Each of the spread apart sections of the stranded conductor is inserted into position within 75 in each of the slots 74 and 75 and thereupon the

plate 73 is pinched at either end to partially close the slots, the slot 75 being shown in the partially closed position which it assumes after the pinching operation. The cable and plate 73 are then held in the assembled relation indicated 5 in Fig. 2 by the provision of a retainer or spacer sleeve 77 of insulating material such as porcelain glass or Bakelite, the upper end of the spacer 77 terminating in the plane of the lower surface of the flanged member 69. Also the upper outer 10 surface of the spacer 77 is in contact with the inwardly and downwardly turned end of a ferrule 79 of low thermal conductivity, the outer portion of which rests upon the shoulder 81 formed near the upper end of the heat dissipating inner wall 15 14 of the shield extension assembly.

As above indicated, one of the important features of the invention concerns the outer or grounded electrode and method of its manufacture and installation. The first step is to secure 20 an H shaped metallic piece 86 of suitable heat and spark resisting qualities while at the same time a sufficiently good conductor. Such a piece is indicated in Fig. 4. This piece is then subjected to a bending operation to bring it into 25 substantially the form indicated in Fig. 5. Next the parallel sides 87 and 88 are turned into semi-circular arcs which preferably do not quite join (as indicated in Figs. 6 and 7) the cross-connecting portion remaining in the form to which it is 30 initially bent, as shown in Fig. 5. The final step in formation of the electrode is to shape the upper annular surface formed by the semi-circular parts 87 and 88 so that in transverse section 35 it will have the final appearance indicated in Fig. 2. When thus completed the electrode receives a thin dished washer 91 of soft metal such as copper and then a second dished washer 92 of harder material and preferably the same material as the electrode 86 itself. The installation and completion of the electrode assembly 40 is then obtained in the following manner: The shell 36 is placed on a table or work-bench with its lower counterbore 94 uppermost, a thin cup-shaped liner 95 of soft metal, preferably the 45 same material as that of the piece 91, and centrally apertured to a diameter corresponding to the diameter of the chamber 34, is then inserted in the recessed end 96. The electrode assembly consisting of the parts 86, 91 and 92 is then 50 placed in position within the inverted cup member 95 and the assembly consisting of the parts 36, 97, 92, 91 and 86, is then placed in a hydrogen gas furnace or other suitable heat chamber and subjected to a temperature sufficient to 55 cause a fusion or welding along the surfaces of the elements 97 and 91, with the result that the five elements above enumerated become fused into a permanently welded single unit. This unit is then removed from the furnace, the core 60 assembly, the shield extension assembly, and upper cable assemblies successively attached thereto in the respective manners above indicated. When this complete assembly has been accomplished it will be found that the inner electrode 25 occupies 65 a position approaching that of the transverse portion 86 of the outer electrode and also approaching that of the inner cylindrical edge 89 of the thimble 92, forming an auxiliary spark gap, the clearances therebetween being such that 70 the spark will normally jump from the relatively broad surface of the electrode 25 to the correspondingly broad plane surface of the cross-piece 86 of the ground electrode; but if for any reason this normal path of the spark is obstructed—as for 75

example by the formation of ice particles—the spark can then jump from the cylindrical surface of the electrode 25 to the above described cylindrical surface 99 of the thimble 92 which 5 may therefore be considered as a part of the completed electrode. In fact, it is, of course, possible to have the elements 92, 91 and 86 originally formed as an integral whole rather than being composed of three subsequently united pieces as 10 shown.

It will be noted that the mica tube 46 terminates somewhat above the lower flange of the heat conducting sleeve 23 of copper or other metal, and that therefore a plurality of the mica 15 disks 18 lie between the end of the mica tube and the said flanged portion of the sleeve. This arrangement has the advantage of facilitating maximum heat transfer from the mica assembly 18 and deflecting such heat to the jacket 24 as 20 well as to the sleeve 22, and at the same time provides a better degree of protection for the lower ends of the layers constituting the completed tube 46. It will also be observed that the cylindrical portion of the sleeve 23 is externally 25 tapered to facilitate a snug grip and seal between parts 46, 23 and 24.

What is claimed is:

1. In a spark plug having a central spindle surrounded by a stack of insulating discs, and an 30 enclosing shell, the combination with said discs, spindle and shell of metallic means including a pressure gland and a flanged sleeve extending through apertures in said discs for facilitating rapid transfer of heat from said discs to said shell the flanged part of said sleeve being in contact with said pressure gland.

2. In a spark plug having a central spindle surrounded by a stack of insulating discs, and an enclosing shell, the combination with said discs, 40 spindle and shell of metallic means including a pressure gland and a flanged sleeve extending through apertures in said discs for facilitating rapid transfer of heat from said discs to said shell the flanged part of said sleeve being in contact 45 with said pressure gland, and a compressible hoop or washer thermally co-operating with said pressure gland, and also with said shell.

3. A spark plug comprising a shell, an electrode supported in the shell, a tube of insulation 50 disposed around the electrode, a soft metallic sealing bushing of high heat conductivity disposed centrally of the electrode and in intimate thermal contact with the insulation, said bushing having formed thereon a flange in contact with the shell, additional insulating material around the electrode above and below the bushing, and a retaining 55 means insertable between the bushing and shell to hold the parts in the shell.

4. A spark plug comprising a shell, an electrode 60 supported in the shell, a tube of insulation disposed around the electrode, a soft metallic sealing bushing of high heat conductivity disposed centrally of the electrode and in intimate thermal contact with the insulation, said bushing having 65 contact with the shell, additional insulating material around the electrode above and below the bushing, and a retaining means insertable between the bushing and shell to hold the parts in the shell, said retaining means being formed to receive a radio shielding means.

5. A spark plug comprising a shell, an electrode supported in the shell, a tube of insulation disposed around the electrode, a soft metallic sealing 70 bushing of high heat conductivity disposed centrally of the electrode and in intimate thermal

contact with the insulation, said bushing having formed thereon a flange in contact with the shell, and a retaining means insertable between the bushing and shell to hold the parts in the shell, said electrode being formed with a bore extending all the way down to the bushing to reduce the cross-sectional area of the electrode above the bushing.

6. A spark plug comprising a shell, an electrode supported in the shell, a tube of insulation disposed around the electrode, a soft metallic sealing 10 bushing of high heat conductivity disposed centrally of the electrode and in intimate thermal contact with the insulation, said bushing having formed thereon a flange in contact with the shell, and a retaining means insertable between the bushing and shell to hold the parts in the shell.

7. A spark plug comprising a shell, an electrode supported in the shell, a tube of insulation disposed around the electrode, a soft metallic sealing bushing of high heat conductivity disposed centrally of the electrode and in intimate thermal contact with the insulation, said bushing having formed thereon a flange fitting within the shell, and a retaining means insertable between the bushing and shell to hold the parts in the shell.

8. A spark plug comprising a shell, an electrode supported in the shell, a tube of insulation disposed around the electrode, a soft metallic sealing bushing of high heat conductivity disposed centrally of the electrode and in intimate thermal contact with the insulation, said bushing having formed thereon a flange fitting within the shell, additional insulating material around the electrode above and below the bushing, and a retaining means insertable between the bushing and shell to hold the parts in the shell, said retaining means being formed to receive a radio shielding means.

9. A spark plug comprising a shell, an electrode supported in the shell, a tube of insulation disposed around the electrode, a soft metallic sealing bushing of high heat conductivity disposed centrally of the electrode, a sealing bushing disposed centrally of the electrode and in intimate thermal contact with the insulation, said bushing having formed thereon a flange in contact with the shell, additional insulating material around the electrode above and below the bushing, and a retaining means insertable between the bushing and shell to hold the parts in the shell.

10. A spark plug comprising a shell, an electrode supported in the shell, a tube of insulation disposed around the electrode, a soft metallic sealing bushing of high heat conductivity disposed centrally of the electrode and in intimate thermal contact with the insulation, said bushing having formed thereon a flange in contact with the shell, additional insulating material around the electrode above and below the bushing, and a retaining means to hold the parts in the shell, said retaining means including a member which, when screwed into the shell, applies pressure to said shell contacting flange.

11. A spark plug comprising a shell, an electrode supported in the shell, a tube of insulation disposed around the electrode, a soft metallic sealing bushing of high heat conductivity disposed centrally of the electrode and in intimate thermal contact with the insulation, said bushing having formed thereon a flange through which heat flow occurs to facilitate cooling of the plug, additional insulating material around the electrode above and below the bushing, and a re-

taining means to hold the parts in the shell, said retaining means including a member which, when screwed into the shell, applies pressure to said sealing bushing.

5 12. A spark plug comprising a shell, an electrode supported in the shell, a tube of insulation disposed around the electrode, a soft metallic sealing bushing of high heat conductivity dis-

posed centrally of the electrode and in intimate thermal contact with the insulation, said bushing having contact with the shell, additional insulating material around the electrode above and below the bushing, and a retaining means insertable between the bushing and shell to hold the parts in the shell.

EDWARD B. NOWOSIELSKI.
